United States Patent Office

Des. 185,915

Patented Aug. 18, 1959

185,915

CHARM

Bert Walter Strassburger, New York, N.Y.

Application October 25, 1957, Serial No. 48,239

Term of patent 3½ years

(Cl. D45—17)

FIG.1

Fig. 1 is a front elevational view of the charm showing my new design;

Fig. 2 is a rear elevational view of Fig. 1; and

Fig. 3 is an end view of the charm of Fig. 1. The dominant features of my design reside in the portions shown in full lines.

I claim:

The ornamental design for a charm, substantially as shown and described.
